N. HILL.

MOP CLOTH HOLDER.

APPLICATION FILED, APR. 5, 1922.

Patented Dec. 12, 1922.

Inventor

Nikolai Hill

By

Attorney

UNITED STATES PATENT OFFICE.

NIKALAI HILL, OF MELLEN, WISCONSIN.

MOP-CLOTH HOLDER.

Application filed April 5, 1922. Serial No. 549,935.

To all whom it may concern:

Be it known that I, NIKALAI HILL, a citizen of the United States, residing at Mellen, in the county of Ashland, State of Wisconsin, have invented certain new and useful 5 Improvements in Mop-Cloth Holders; and I do hereby declare the following to be a full, clear, and exact description of the invention, such as will enable others skilled in 10 the art to which it appertains to make and use the same.

This invention relates to new and useful improvements in mops and particularly to clamps for holding the cloths thereof.

15 One object of the invention is to provide a clamp including a pair of toothed jaws, with novel and effective means for drawing the jaws together, in gripping relation to a cloth, and means for locking the holding 20 means to prevent accidental disengagement thereof.

Other objects and advantages will be apparent from the following description when taken in connection with the accompanying 25 drawing.

In the drawing:

Figure 1 is an elevation of a mop head made in accordance with the present invention, the jaws of the holder being shown in 30 open position.

Figure 2 is an edge view of the device, in the position of Figure 1, looking into the open jaws thereof.

Figure 3 is a fragmentary side elevation 35 of the clamping jaws and locking means, with the jaws in closed position.

Referring particularly to the accompanying drawing, 10 represents a portion of the handle, which has the ferrule 11 secured 40 thereon, and which ferrule is provided with the longitudinally extending parallel blades 12, for the reception therebetween of the stem 13 of the stationary jaw 14, of the holder. This jaw is approximately crescent- 45 shaped, and extends transversely of the outer end of the stem 13, the outer convex edge face of the jaw being serrated, as shown at 15. A second crescent-shaped jaw 16, has one end pivotally connected to one end of the 50 fixed jaw 14, as shown at 17, and on its other end there is pivotally mounted a wire loop 18. It will be noted that the concave edge

face of the jaw 16 is directed for cooperation with the convex edge face of the jaw 14, to clamp a mop cloth therebetween, the jaw 16 55 having serrations 19 along its concave edge face.

Pivotedly mounted on the other end of the fixed jaw 14 is a lever 20, the inner, or pivotal end of which is formed with a hook 60 21, which, when the loop 18 is engaged on the lever, and the lever swung over toward the stem of the jaw 14, will pull the loop, and also the pivoted jaw 16 toward the jaw 14, the loop finally resting within the hook 65 above the unserrated edge face of the jaw 14. Bent over from the unserrated edge of the lever-carrying end of the jaw 14, is a tab or tongue 22, past which the bill of the hook 21 snaps, as the lever is moved into jaw 70 drawing position, for the purpose of engagement with said bill hook, to hold the same against swinging back, and releasing the jaw 16, from gripping relation to the mop cloth. 75

To release the lever from the tongue 22, it is necessary to move the lever laterally, so that the bill will pass outwardly beyond the tip of the tongue, when the lever may be swung over, into the position of Figure 1, 80 thus permitting the jaw 14 to be swung away from the jaw 16, and release the cloth, from between the jaws.

What is claimed is:

A mop cloth clamp comprising a pair of 85 jaws pivotally connected at one end, a lever pivotally mounted on the other end of one of the jaws and having a hook on its pivotal portion, a pivoted loop on the end of the other jaw corresponding to the lever end 90 of the first jaw for engagement on the lever and movement into embracing relation to the said end of the first jaw when the lever is swung on its pivot, and a detent on the first jaw for engagement by the bill of the 95 hook to prevent displacement of the lever from locked position.

In testimony whereof, I affix my signature, in the presence of two witnesses.

NIKALAI HILL.
